UNITED STATES PATENT OFFICE

GEORGE C. CHERBONNIER, OF FERGUSON, MISSOURI, ASSIGNOR TO AMERICAN CAR & FOUNDRY COMPANY, OF ST. LOUIS, MISSOURI, A CORPORATION OF NEW JERSEY.

DOOR-OPERATING MECHANISM.

No. 905,128

Specification of Letters Patent.

Patented Nov. 24, 1908.

Application filed January 18, 1908. Serial No. 411,451.

To all whom it may concern:

Be it known that I, GEORGE CASE CHERBONNIER, a citizen of the United States, residing at Ferguson, Missouri, have invented 5 a certain new and useful Improvement in Door-Operating Mechanism, of which the following is a full, clear, and exact description, such as will enable others skilled in the art to which it appertains to make and use 10 the same, reference being had to the accompanying drawings, forming part of this specification, in which—

Figure 1 is a top plan view of a portion of a car provided with a door-operating mechanism constructed in accordance with my invention; Fig. 2 is a sectional view taken on the line 2—2 of Fig. 1; Fig. 3 is an enlarged perspective view of one of the door-supporting devices and the bracket on the door to 20 which said device is connected; and Fig. 4 is a detail view showing the tooth on the winding shaft which is adapted to engage a coöperating tooth on the door-supporting device to move it into an inoperative position.

25 This invention relates to door operating mechanisms for dump cars, and has for its object to provide a mechanism of the character described that is of simple construction and which will remove the strain from the 30 door-operating chain when the door is in its closed position.

Referring to the drawings which illustrate the preferred form of my invention, 1 designates a hinged door that closes an opening in 35 the bottom of a car, and 2 designates a rotatable winding shaft to which the door-operating chains 3 are fastened. The door is provided at its front edge with members that rest on the winding shaft 2 when the 40 door is closed so as to remove the strain from the winding chains, said members consisting of devices 4 pivotally connected to brackets 5 on the underneath side of the door, as shown in Fig. 2. The devices 4 are preferably formed from cast metal and each has a shoulder or bearing surface 4^a that is adapted to rest upon a collar 6 on the winding shaft 2 when the door is closed. A housing 7 projects laterally from one side of the device 4 to receive an eye-bolt 8 to which the winding chain 3 is connected, as shown in dotted lines in Fig. 2, and the top wall of said housing is curved upwardly at 9 to form a guide for the chain, said upwardly curved 50 portion 9 also operating to prevent the de-

vice 4 from becoming wedged underneath the shaft 2 when the door is being moved into its closed position as hereinafter more fully described. The device 4 is provided at its rear side with a laterally projecting flange 60 10 and one of the depending ears 11 on the bracket 5 is provided with a laterally projecting lug 12 that coöperates with the flange 10 on the device 4 and thus forms a stop that limits the swinging movement of the device 65 4 outwardly or toward the shaft 2, the lug 12 on the bracket being strengthened by a rib 13 formed integral with the ear 11 of the bracket.

On the side of the device 4 opposite to 70 that from which the housing 7 projects, is a tooth 14, and the sleeve 6 on the winding shaft is provided with a coöperating tooth or lug 15 that engages the tooth 14 on the device 4 and swings it away from the winding shaft 2 when said shaft is moved in the direction for permitting the door to swing 75 downwardly. It should be understood, however, that various other means could be employed for swinging the device 4 away from 80 the winding shaft without departing from the spirit of my invention. For example, the sleeve 6 on the winding shaft could be provided with a ratchet that engaged the device 4 and moved it away from the shaft, 85 or the sleeve 6 and the device 4 could be provided with coöperating roughened surfaces that would cause said device to swing away from the shaft when the shaft was rotated. 90

The operation of the device is as follows: The winding shaft 2 is rotated to cause the chains 3 to be wound onto same and thus move the door into its closed position and when said door arrives in its 95 closed position the devices 4 on the door engage the collars 6 on the winding shaft and thus remove the strain from the chains 3. The lugs 12 on the brackets limit the outward movement of the devices 4 toward 100 the winding shaft while the door is being raised and the upwardly curved portions 9 on the housings 7 bear against the chains 3 as the door is moving into its closed position and cause the devices 4 to swing rearwardly away from the winding shaft as 105 said devices 4 approach the shaft, thus preventing the devices 4 from catching or becoming wedged underneath the winding shaft. When the door is to be opened the 110

winding shaft is rotated in the reverse direction and the teeth 15 or other means on said shaft engage the teeth 14 on the devices 4 and move said devices out of engagement with the winding shaft so that the door can drop, the curved portions 9 on the devices 4 also forming guides for the winding chains as the door swings downwardly. The bearing face 4^a on each of the devices 4 is preferably formed on the arc of a circle, the center of which is the pivot that connects said device to the bracket 5. The advantage of providing the device 4 with a curved bearing face 4^a of this form is that said device can occupy various positions relatively to the collar 6 on the winding shaft and still retain the door in its closed position.

Having thus described my invention, what I claim as new and desire to secure by Letters Patent is:

1. In a door-operating mechanism, a hinged door, a rotatable shaft, a device pivotally connected to the underneath side of the door adjacent its front edge and depending downwardly from said door, and a flexible member connected to the shaft and to said device, said device being so formed that it rests upon the shaft when the door is closed and thus transmits the weight which the door carries directly to said shaft which lies in a lower horizontal plane than the door; substantially as described.
2. In a door-operating mechanism, a hinged door, a rotatable shaft, a flexible member connected to said door and shaft for moving the door into its closed position, a bracket on the underneath side of the door, a device pivotally connected to said bracket and adapted to rest upon said shaft when the door is closed, and coöperating means on said device and bracket for limiting the movement of said device in one direction; substantially as described.
3. In a door-operating mechanism, a hinged door, a rotatable shaft, a flexible member connected to said door and shaft for moving the door into its closed position, a bracket on the underneath side of the door, a device pivotally connected to said bracket and adapted to rest upon said shaft when the door is closed, coöperating means on said device and bracket for limiting the movement of said device in one direction, a tooth projecting laterally from one side of said device, and a coöperating tooth on the shaft which is adapted to engage the tooth on said

device and move the device out of engagement with the shaft when it is rotated in one direction; substantially as described.

4. In a door-operating mechanism, a hinged door, a rotatable shaft, a bracket connected to the underneath side of said door, a device pivotally connected to said bracket and provided with a laterally projecting housing having its top wall curved upwardly, a chain secured to the shaft and to the housing on said device, said device having a bearing face which rests on the shaft when the door is closed, a flange on the rear side of said device, and a lug on the bracket which coöperates with the flange on said device and limits its swinging movement in one direction; substantially as described.

5. A door-operating mechanism comprising a winding shaft, a hinged door, a device pivotally connected to the door and adapted to rest upon the winding shaft when the door is in its closed position, a flexible member connected to said shaft and to the pivotally mounted device on the door to raise said door, and means on said device which bears against said flexible member so as to prevent said device from wedging underneath the shaft when the door is being raised; substantially as described.

6. A door-operating mechanism comprising a winding shaft, a hinged door having a device pivotally connected thereto which is adapted to rest on said shaft when the door is closed, a flexible member connected to said shaft and to the device on the door, and an upwardly curved flange on said device which bears against said flexible member when the door is moving into its closed position; substantially as described.

7. In a door-operating mechanism, a hinged door, means for raising said door, and a pivotally mounted device arranged on the underneath side of said door and provided with a curved bearing face that rests on a support when the door is closed, said curved bearing face being concentric with the pivot of said device so that the door will remain in its closed position whenever any portion of said curved bearing face rests on the support; substantially as described.

In testimony whereof I hereunto affix my signature in the presence of two witnesses, this fifteenth day of January 1908.

GEORGE C. CHERBONNIER.
